UNITED STATES PATENT OFFICE.

FRANK B. MARTIN, OF BATTLE CREEK, MICHIGAN, ASSIGNOR TO POSTUM CEREAL CO. LIMITED, OF BATTLE CREEK, MICHIGAN, A PARTNERSHIP.

CAN FILLING AND SEALING MACHINE.

1,197,753.

Specification of Letters Patent. Patented Sept. 12, 1916.

Application filed April 27, 1914. Serial No. 834,750.

To all whom it may concern:

Be it known that I, FRANK B. MARTIN, of Battle Creek, Michigan, have invented a new and useful Improvement in Can Filling and Sealing Machines, which invention is fully set forth in the following specification.

This invention relates to machines designed to automatically supply a measured quantity of granular material to receptacles such as cans, and after the same is supplied, to automatically and hermetically seal the same.

The objects of the invention are to provide a structure of this character which shall handle the cans or other receptacles without injury thereto, place a predetermined amount of material in the cans, seal the same, as by forcing a slightly tapering closure into the can opening, and then discharge the can or receptacle from the machine, and deliver it to any desired point, the whole being conducted in such a manner as to preserve the exterior of the can clean and free from the granular material, supply each can with the same amount of material, close it hermetically, and deliver the can with rapidity and without marring or injuring the same.

With these objects in view, the invention consists in providing an intermittently operating carrier associated with suitable can feeding devices, measuring devices and sealing or closure mechanism, each of which performs its particular function during the periods of rest occurring between the intermittent movements of the carrier.

The invention further resides in certain details of construction which will be best understood from a reading of the accompanying specification.

The inventive idea may be embodied in a variety of mechanical constructions, one of which, for the purpose of illustration, is shown in the accompanying drawings, which drawings, however, are designed for illustrative purposes only, and are not to be taken as defining the limits of the invention, reference being had to the appended claims for this purpose.

In said drawings—Figure 1 is a perspective view of the machine; Fig. 2 is a side elevation looking from the left-hand side of Fig. 1; Fig. 2^a is a detail showing the construction of the intermittent carrier; Fig. 3

is a side elevation on the opposite side from that shown in Fig. 2; Fig. 4 is an elevation looking from the left in Fig. 2; Fig. 5 is a sectional detail of the hopper and measuring device, taken on the line 5—5 of Fig. 4, 60 and showing the measuring device in the position it occupies in discharging a measured quantity of material; Fig. 6 is a sectional detail, similar to Fig. 5, with the measuring device in position to receive a charge of material from the hopper; Fig. 7 is a horizontal section taken on the line 7—7 of Fig. 2; and Fig. 8 is a like section, taken on the line 8—8 of Fig. 2.

Referring to the drawings, in which like reference characters indicate like parts throughout the several views, 1 indicates the framework of the machine, and 2 the driving belt leading from any suitable source of power to a pulley 3 on a shaft 4, in bearings 70 on the side of the frame 1, and having a gear wheel 5 thereon meshing with a gear 6 on a short shaft 7, having bearings in a swinging bracket 8 hung to the shaft 4. The bracket 8 has an arm 9 extending upward and on the opposite side of the shaft 4 from the gear 6, and is connected by a link 10 to an eccentric 11 on a shaft 12 having bearings in the framework of the machine, and provided with a lever arm or crank handle 13, by means of which the shaft 12 may be rocked (see Figs. 3, 4 and 7).

A horizontal shaft 14 has a gear wheel 15 keyed thereto, and when the machine is in operation, this gear wheel 15 is in mesh with the gear 6. On the opposite end of the shaft 14 from the gear 15 is a disk 16, having a pawl 17 pivoted thereto and co-operating with a ratchet 18 (here shown as a six-tooth ratchet), keyed to a shaft 19 (see Figs. 1 90 and 8). This shaft 19 has a bevel gear 20 thereon meshing with a bevel gear 21 on a vertical shaft 22, which carries on its upper end a disk-like conveyor 23, provided with a suitable number of pockets 24 for receiving the cans or other receptacles, the said pockets being shaped to correspond to the shape of the cans and snugly hold the same. The shaft 22 has a collar 25 (Fig. 2) keyed thereto, and the disk 23 is also preferably 100 provided with a collar 26, by means of which it is keyed to the shaft, the two collars affording the support for the vertical thrust of the shaft, which shaft is provided with bearings 27 suitably mounted in the frame.

work above the bevel gear 21, and which also takes bearing in a stationary table 28 located immediately below the disk 23. This table 28 is provided with a notch or opening 29 (Fig. 2^a) for the reception of the feed belt, and a discharge opening 30 immediately over a spout or chute 31, leading downward to an off-bearing belt 32.

Supported in the framework of the machine is a hopper 33 (Figs. 2 and 5) containing the material to be supplied to the cans. The lower end of said hopper is formed as a cylindrical spout or tube 34, and immediately below the latter is a funnel-like structure 35 with a downwardly directed opening 36, through which the material is delivered to the cans. The rod 37 extends downward through the hopper, and bears on its lower end two reversely placed, conical-shaped valves 38, 38', screw-threaded thereto, with the apex of the cones adjacent to each other. These valves 38 and 38' at their largest diameter fit snugly within the tubular portion 34, and are provided at their bases with sharp scraping edges 39, 39'. Means are provided for reciprocating the rod 37, so as to move the valves 38, 38' upward and downward in the tubular portion 34, the proportion of the parts being such that the upper position of the scraping edge 39' of the valve 38' is above the lower position of the scraping edge 39 of the valve 38 at the extreme of its downward movement, to the end that the entire inner surface of the tubular portion 34 is subjected to the cleaning and scraping action of the edges 39, 39', on each reciprocation of the rod 37. This is of importance when handling material which, because of its hydroscopic properties, is liable to become sticky when exposed to the atmosphere, and unless the same were cleanly scraped from the interior of the tubular portion 34, the amount sticking to the interior thereof would interfere with the free passage of the material, and would also render it impossible to deliver exactly the same quantity at each reciprocation. When the rod 37 is in its upper position, shown in Fig. 6, the granular material feeds downward, as shown, below the valve 38, and above the valve 38', and as the rod 37 and the two valves thereon descend, a definite portion of the material is confined in the tubular portion 34 between said valves, until the valve 38' descends below the opening of said tubular portion 34, as shown in Fig. 5, when all of the material below the valve 38 is discharged into the funnel-like receptacle 35 and through the opening 36 thereof. As above described, this also results in the cleaning or scraping action of the valve edges 39, 39' against the interior walls of the tubular portion 34.

For the purpose of imparting the desired reciprocation to the rod 37, a divided rock-

ing lever 40 is pivoted at 41 to a bracket 42 secured to the top of the frame 1 of the machine, the two sides of said lever 40 being provided with slots 43, in which play trunnions 44 projecting from the sides of the rod 37, to the end that the rocking movements of the lever 40 shall not interfere with the vertical movement of the rod. Preferably, the lever 40 is counterbalanced by a suitable weight 45, and the rocking movement of said lever is imparted to it through a rod 46 passing through and playing freely in a guide block 47, pivoted between the two parts of the lever 40. The rod 46 is provided with a collar 48 keyed thereto above the lever 40, and a collar 49 keyed thereto below the lever 40, and if desired, buffer springs 50 may be interposed between said collars and the lever 40, as shown. The lower end of the rod 46 is pivotally connected to an arm 51 (Fig. 1) keyed to a rock shaft 52 having suitable bearings in the framework of the machine. This shaft has rocking movement imparted to it through arm 53 keyed thereto and pivotally connected to a rod 54, which is eccentrically connected at its lower end to gear wheel 15 on the shaft 14.

Mounted to reciprocate through bracket bearing 55 (Fig. 4), secured to the framework of the machine, is a plunger rod 56, which has a collar 57 keyed thereto, between which and the lower bracket arms 55 a spring 58 reacts. Keyed to the shaft 52 is an arm 59, extending outward over the top of the plunger rod 56, and when the shaft 52 is rocked downward, said arm 59 impinges on the top of the plunger 56, and depresses it against the tension of spring 58. The plunger rod 56 carries on its lower end a tool 60, suitably shaped to force the can closure into the opening of the can so tightly as to hermetically seal it, in a way common in the art.

It will be observed that when the rock shaft 52 is rocked downward, it not only forces the plunger rod 56 downward, but at the same time actuates the valve rod 37 in the measuring and feeding hopper 33.

For the purpose of feeding the cans to the carrier 23 and inserting them in the pockets 24 thereof, there is provided an endless feed belt 61, passing over a suitable pulley 62 mounted on a shaft 63 driven by sprocket-chain 64, which passes over a sprocket wheel on shaft 65, which shaft in turn is driven by sprocket chain C6 from shaft 14. The feed belt 61 has its upper flight on a level with the upper surface of the stationary table 28, and the pulley 62 is so located that the belt passes into the opening 29 formed in said table, and as its upper surface is on a level with the upper surface of the table, the can, with its bottom resting on the belt, is in a position to

be slid off of the belt onto the table. The cans are fed in an upright position into the pocket 24 in the intermittently revolving carrier 23 that is immediately over the opening 29 in the stationary table, being guided into said opening by rails 67 (Fig. 1), placed opposite each other, just above the surface of the upper flight of the belt 61, as will be readily understood from an inspection of Fig. 1.

The shaft 19 is provided with a second ratchet wheel 68 (Fig. 1) which, like ratchet wheel 18 on said shaft, is a six-tooth ratchet, but is placed on the shaft with the teeth thereon facing the reverse of those on the ratchet wheel 18, and a stop device co-operates with said ratchet wheel to stop the revolution of the shaft 19 just at the end of the throw effected by the pawl 17 and ratchet 18, and thereby prevent any overthrow. This stop device is in the form of a lever 69 (Fig. 3) pivoted at 70 to the frame of the machine, and having a shoulder 71 projecting downward in the path of the teeth on the ratchet wheel 68. The lever 69 extends over the ratchet wheel 68 and over the shaft 14, in position to be lifted by a cam 72 on the shaft 14, the action of which cam is so timed that it engages the lever 69 and lifts it so as to remove the stop shoulder from in front of the teeth on the ratchet wheel 68, just before the pawl 17 engages the teeth on the ratchet wheel 18.

In order to prevent any back-lash of the parts when the pawl 17 throws the ratchet wheel 18 over, and the shoulder 71 engages the teeth of the ratchet wheel 68 and stops the same, there is provided a pivoted lever 73, preferably counterbalanced by a weight 74 (Fig. 1) acting to hold the nose of the lever against the ratchet wheel 18, so that the nose of said lever drops in front of a tooth on the ratchet wheel 18, just as the stop shoulder 71 on the lever 69 drops behind a tooth on the ratchet wheel 68, whereby the two levers 69 and 73 operate to effectually lock the parts in position just at the end of the forward thrust of the pawl 17.

The intermittently revolving table 23 is surrounded by an upwardly projecting flange or rail 75 which, however, is provided with an opening immediately over the feed belt 61, as will be readily understood from an inspection of Fig. 1. This flange or rail 75 is supported in any suitable way, as by angle irons 76 secured to the frame of the machine.

Operation: The hopper 33 being supplied with suitable material, and cans being supplied to the feed belt 61, the cans are fed by said belt, one at a time, into the pockets of the carrier 23, as said pockets come to rest opposite the opening in the flange 75 over the belt. It will be observed

that there are six pockets 24 in the carrier 23, and that there are six teeth to the ratchet wheel 18, and that at the time when the pocket is at rest to receive a can from the feed belt, the next pocket in a clock-wise direction therefrom is immediately under the funnel-like part 35; the third and fourth pockets are opposite exposed parts of the machine; the fifth pocket is immediately under the tool 60 on the plunger rod 56; 75 and the sixth and last pocket 24 is immediately over the opening 30 in the stationary table 28 and above the delivery spout or chute 31. With the parts in this position, the rock shaft 52 is actuated to force the 80 valve rod 37 downward into the position shown in Figs. 4 and 5, and deliver a measured quantity of material into the funnel 35, from whence it passes through the opening 36 in the funnel into the can opening which is immediately beneath the same, the two collars 48 and 49 which actuate the lever 40 being adjusted at such a distance apart as to afford the necessary dwell to permit the material to flow out from between the valves 38, 38', before the rod 37 with the valves is again elevated. At the same time that the rod 37 is lowered by the lever 40, the arm 59 on the shaft 52 depresses the plunger 56, operating to force the can 95 closure or cover tightly into position on the can, said closures having been placed on the cans by hand when the pockets containing the cans were in the third and fourth positions, regarding the position when the can is received from the feed belt as position No. 1. These functions having been performed, the upward movement of the bar 46 elevates the lever 40, throwing the valves 38, 38', into the position shown in Fig. 6, 100 in which, because of the dwell before mentioned, they remain for a sufficient time to permit the material to flow down between the valves, as shown in Fig. 6. While this is taking place, the pawl 17 has shifted the 105 ratchet 18, thus giving the disk 23 a one-sixth revolution, and bringing the next can under the feed hopper, and advancing another can under the closing tool 60, while the can that has just been closed is advanced 110 to the sixth and last position over the opening 30 in the table 28, through which opening it drops down the chute 31 onto the off-bearing belt 32.

The stationary table 28 is provided over 120 a portion of its surface immediately under the hopper 33 with a number of perforations 77 (Fig. 2^a), for the purpose of permitting any portions of the material which may find their way through the pockets 24 onto the surface of the table 28 to escape therefrom downward, and thus avoiding the collection of any considerable amount of the material between the revolving carrier 125 23 and the table 28.

Should it be desired to throw the machine out of operation at any time, the operator has but to grasp the handle on the crank arm 13, and throw it upward from the position shown in Fig. 2, thereby rocking the shaft 12 and shifting the bracket 8, so as to throw the gear 6 out of mesh with the gear 15. When in operative position, the crank arm 13 rests on a stop pin 78, projecting from the frame of the machine.

By means of the construction just described, a completely filled and closed can is discharged at every step in the revolution of the carrier disk 23; and during the intervals of pause between the steps, an empty can is being fed to the disk, one is being filled, and one is being closed. Moreover, it will be observed that the filling mechanism is constructed to accurately measure and supply an exact quantity of material to the cans, the valves 38, 38', being adjustable by reason of their screw-threaded connection with the valve rod 37 and the lock nuts co-operating therewith; and that by reason of the cleaning action of the valves, no material can accumulate on the interior of the tubular portion 34 of the measuring device.

While the machine has been herein described with some particularity, in order that the invention may be readily understood, the invention is not confined to the specific construction shown, nor the particular proportions of the parts, since it will be apparent to anyone skilled in the art that these may be varied within the limits of the claims hereto appended.

What is claimed is:—

1. In a machine of the character described, the combination of an intermittently operated carrier, means for feeding cans thereto during the intervals of rest, devices supplying a measured quantity of material to said cans, mechanism for sealing the cans, and an oscillating rock-shaft simultaneously actuating said supply devices and sealing mechanism.

2. In a machine of the character described, the combination of a carrier, having pockets therein, means for filling cans positioned in the pockets, a pawl and ratchet imparting intermittent movement to the carrier, a stop for preventing overthrow by said pawl and ratchet, and a stop for preventing back-lash, whereby the exact positioning of the said carrier is assured at each stroke of said pawl.

3. In a machine of the character described, the combination of a carrier, means imparting intermittent movement thereto, a can filling device, a can closing device, a rock shaft in operative relation with said filling and closing devices, said shaft having a dwell connection with said filling device.

4. In a can filling and closing machine,

the combination of a can carrier, a filling means for the cans, a closing means for the cans, means for intermittently moving the carrier to successively bring pairs of cans respectively beneath the filling means and 70 the closing means, a shaft having an arm operatively connected to the filling means and an arm operatively connected to the closing means, and mechanism for oscillating the shaft in timed relation with the carrier movements.

5. In a can filling machine, the combination of a carrier having an endless series of can-receiving pockets, means for filling cans in the pockets, two oppositely notched 80 ratchet members operatively connected with the carrier, a reciprocating pawl engaging one ratchet member to intermittently move the carrier, a stop for engaging the other ratchet member to prevent over-travel of the 85 carrier, and means separate from the said pawl for momentarily disengaging the stop from its ratchet member to permit the pawl to move the carrier.

6. In a can filling machine, the combination of a carrier having an endless series of can-receiving pockets, means for filling cans in the pockets, two oppositely notched ratchet members operatively connected with the carrier, a reciprocating pawl engaging 95 one ratchet member to intermittently move the carrier, a stop for engaging the other ratchet member to prevent over-travel of the carrier, means for momentarily disengaging the stop from its ratchet member to permit 100 the pawl to move the carrier, and a second stop for engaging the first ratchet member at the end of each movement to prevent back-lash of the carrier.

7. In a can filling machine, the combination of a carrier having an endless series of can-receiving pockets, means for filling cans in the pockets, a rotatable shaft connected with the carrier to move it, two oppositely notched ratchet wheels on the shaft, a reciprocating pawl engaging one ratchet wheel to intermittently turn the shaft and move the carrier, and a stop for engaging the other ratchet wheel to prevent over-travel of the shaft and carrier.

8. In a can filling machine, the combination of a carrier having an endless series of can-receiving pockets, means for filling cans in the pockets, a rotatable shaft connected with the carrier to move it, two oppositely notched ratchet wheels on the shaft, a reciprocating pawl engaging one ratchet wheel to intermittently turn the shaft and move the carrier, a stop for engaging the other ratchet wheel to prevent over-travel of the 120 shaft and carrier, and a second stop for engaging the first wheel at the end of each movement to prevent back-lash of the carrier.

9. In a can filling machine, the combina-

tion of a carrier having an endless series of can-receiving pockets, means for filling cans in the pockets, a rotatable shaft connected with the carrier to move it, two oppositely notched ratchet wheels on the shaft, a second continuously rotating shaft, a reciprocating pawl eccentrically connected to the second shaft and engaging one ratchet wheel to intermittently turn the first shaft and move the carrier, a stop for engaging the other ratchet wheel to prevent over-travel of the shaft and carrier, and a cam on the second shaft for momentarily disengaging the stop from its wheel to permit the pawl to turn its wheel.

10. In a can filling machine, the combination of a constantly moving belt, a plate having its top flush with the top of the belt, an intermittently moving carrier positioned above the plate and the belt and provided at its edge with spaced pockets open at their tops and bottoms and registering successively with the belt as the carrier moves intermittently, whereby cans placed on the belt are automatically carried thereby into the pockets successively, and means for filling the said cans while in the said pockets.

11. In a can filling machine, the combination of a constantly moving belt, a rotatable disk positioned partly above the belt and provided with spaced peripheral pockets open at their tops and bottoms, a plate beneath the disk with its top flush with the top of the belt, means for intermittently turning the disk to bring the pockets successively over the belt, whereby cans placed on the belt are automatically carried thereby into the pockets successively, and means for filling the said cans while in the said pockets.

12. In a can filling machine, the combination of a constantly moving belt, stationary longitudinal can-guiding rails above the belt, a carrier positioned partly above the belt and provided at its edge with spaced pockets open at their tops and bottoms, a plate beneath the carrier with its top flush with the top of the belt, means for intermittently moving the carrier to bring the pockets successively over the belt and into register with the space between the rails, whereby cans placed on the belt are automatically carried thereby into the pockets successively, and means for filling the said cans while in the said pockets.

13. In a can filling machine, the combination of a constantly moving belt, a rotatable disk positioned partly above the belt and provided with spaced peripheral pockets open at their tops and bottoms, a stationary circumferential rail closely surrounding the disk and imperforate except for a single opening registering with the belt, a plate beneath the disk with its top flush with the

top of the belt, means for intermittently turning the disk to bring the pockets successively over the belt and into register with the opening in the rail, whereby cans placed on the belt are automatically carried thereby into the pockets successively, and means for filling the said cans while in the said pockets.

14. In a can filling machine, the combination of a constantly moving belt, stationary longitudinal can-guiding rails above the belt, a rotatable disk positioned partly above the belt and provided with spaced peripheral pockets open at their tops and bottoms, a stationary circumferential rail closely surrounding the disk and imperforate except for a single opening registering with the space between the longitudinal rails, a plate beneath the disk with its top flush with the top of the belt, means for intermittently turning the disk to bring the pockets successively over the belt and into register with the opening in the circumferential rail, whereby cans placed on the belt are automatically carried thereby into the pockets successively, and means for filling the said cans while in the said pockets.

15. In a can filling machine, the combination of a carrier provided at its edge with spaced pockets open at their tops and bottoms, a supporting plate beneath the carrier provided with a discharge opening, means for intermittently moving the carrier to bring the pockets successively over the discharge opening, whereby cans positioned in the pockets are automatically discharged by gravity successively through the said discharge opening, and means for filling the said cans while in the said pockets.

16. In a can filling machine, the combination of a rotatable disk provided with spaced peripheral pockets open at their tops and bottoms, a supporting plate beneath the carrier and provided with a discharge opening, means for intermittently rotating the disk to bring the pockets successively over the discharge opening, whereby cans positioned in the pockets are automatically discharged by gravity successively through the said discharge opening, and means for filling the said cans while in the said pockets.

17. In a can filling machine, the combination of a rotatable disk provided with spaced peripheral pockets having their tops and bottoms open, a stationary circumferential rail closely surrounding the disk and imperforate except for a single opening for the feeding of cans into the said pockets, a supporting plate beneath the disk provided with a discharge opening, means for intermittently turning the disk to bring the pockets successively over the discharge opening, whereby cans positioned in the pockets are automatically discharged by gravity suc-

cessively through the said discharge opening, and means for filling the said cans while in the said pockets.

18. In a can filling machine, the combination of a constantly moving belt, a carrier positioned partly above the belt and provided at its edge with spaced pockets open at their tops and bottoms, a plate beneath the carrier provided with a discharge opening and having its top flush with the top of the belt, means for intermittently moving the carrier to bring pairs of pockets successively into register respectively with the belt and with the discharge opening, whereby cans placed on the belt are automatically carried thereby into the pockets successively and whereby cans in the pockets are automatically discharged therefrom by gravity through the said discharge opening successively, and means for successively filling the said cans while in the said pockets.

19. In a can filling machine, the combination of a constantly moving belt, a rotatable disk positioned partly above the belt and provided with spaced peripheral pockets open at their tops and bottoms, a plate beneath the disk provided with a discharge opening and having its top flush with the top of the belt, means for intermittently turning the disk to bring pairs of pockets successively into register respectively with the belt and with the discharge opening, whereby cans placed on the belt are automatically carried thereby into the pockets successively and whereby cans in the pockets are automatically discharged therefrom by gravity through the said discharge opening successively, and means for successively for filling the said cans while in the said pockets.

20. In a can filling machine, the combination of a constantly moving belt, stationary longitudinal can-guiding rails above the belt, a rotatable disk positioned partly above the belt and provided with spaced peripheral pockets open at their tops and bottoms, a stationary circumferential rail closely surrounding the disk and imperforate except for a single opening registering with the space between the longitudinal rails, a plate beneath the disk provided with a discharge opening and having its top flush with the top of the belt, means for intermittently turning the disk to bring pairs of pockets successively into register respectively with the belt and with the discharge opening, whereby cans placed on the belt are automatically carried thereby into the pockets successively and whereby cans are automatically discharged from the pockets by gravity through the said discharge opening successively, and means for successively filling the said cans while in the said pockets.

21. In a can filling machine, the combination of two constantly moving conveyer belts

having their active strands at different levels, a movable carrier positioned partly above the upper belt and provided at its edges with spaced pockets open at their tops and bottoms, a plate beneath the disk provided with a discharge opening and having its top flush with the top of the upper belt, means for intermittently turning the disk to bring pairs of pockets successively into register respectively with the belt and with the discharge opening, whereby cans placed on the belt are automatically carried thereby into the pockets successively and whereby cans are automatically discharged from the pockets by gravity through the said discharge opening successively, means for guiding the cans from the discharge opening to the lower belt, and means for successively filling the said cans while in the said pockets.

22. In a can filling machine, the combination of a hopper having a spout at its lower end, means for positioning cans beneath the spout, a rod vertically reciprocating in the hopper, and two cones on the rod with their larger ends opposite each other and snugly fitting the spout, the said larger ends being provided with sharp scraping edges.

23. In a can filling machine, the combination of a hopper having a spout at its lower end, means for positioning cans beneath the spout, a rod vertically reciprocating in the hopper, and two cones on the rod with their larger ends opposite each other and snugly fitting the spout, the said larger ends being provided with sharp scraping edges, the said cones being adjustable on the rod toward and from each other.

24. In a can filling machine, the combination of a hopper having a spout at its lower end, means for positioning cans beneath the spout, a rod vertically reciprocating in the hopper, two cones on the rod with their larger ends opposite each other and snugly fitting the spout, the said larger ends being provided with sharp scraping edges, and a funnel below the bottom of the spout and above the cans, the upper end of the funnel being larger than the spout.

25. In a can filling machine, the combination of a hopper having a spout at its lower end, means for positioning cans beneath the spout, a rod vertically movable in the hopper, two cones on the rod with their larger ends opposite each other and snugly fitting the spout, the said larger ends being provided with sharp scraping edges, and means for vertically reciprocating the rod and giving it a dwell at each end of each reciprocation.

26. In a machine of the character described, the combination of a hopper having a spout at its lower end, means for positioning cans beneath the spout, a rod vertically reciprocable in the hopper, two cones on the rod with their larger ends opposite each

other and snugly fitting the spout, the said larger ends being provided with sharp scraping edges, and means for reciprocating the rod to cause the said scraping edge to engage the entire inner surface of the spout during each cycle of reciprocations.

27. In a device of the character described, the combination of a hopper having a spout at its lower end, means for supporting cans beneath the spout, a rod vertically reciprocating in the hopper, and two cones

on the rod with their larger ends opposite each other and snugly fitting the spout, the said larger ends being provided with sharp scraping edges.

In testimony whereof I have signed this specification in the presence of two subscribing witnesses.

FRANK B. MARTIN.
